US0D1013728S

(12) **United States Design Patent** (10) **Patent No.:** **US D1,013,728 S**
(45) **Date of Patent:** **** Feb. 6, 2024**

(54) **DISPLAY PANEL OR PORTION THEREOF
WITH A GRAPHICAL USER INTERFACE**

(71) Applicant: **Solidus Ventures GmbH**, Schlieren (CH)

(72) Inventors: **Eliot Samuels**, New York, NY (US);
Daniel Frauchiger, Thalheim (CH);
Andrew Moedinger, Schlieren (CH);
Samuel Gaw, New York, NY (US)

(73) Assignee: **SOLIDUS VENTURES GMBH**, Schlieren (CH)

(**) Term: **15 Years**

(21) Appl. No.: **29/722,935**

(22) Filed: **Feb. 3, 2020**

CLAIM

The ornamental design for a display panel or portion thereof with a graphical user interface, as shown and described.

DESCRIPTION

FIG. 1 is a front view of a display panel or portion thereof with a graphical user interface showing our new design; FIG. 2 is a front view of a second embodiment thereof; FIG. 3 is a front view of a third embodiment thereof; and, FIG. 4 is a front view of a fourth embodiment thereof. The outermost broken lines illustrate showing of a display panel or portion thereof and form no part of the claimed design. The remaining broken lines illustrate portions of the graphical user interface and form no part of the claimed design.

1 Claim, 4 Drawing Sheets

Related U.S. Application Data
